Term of patent 3½ years

Int. Cl. D6—01

U.S. Cl. D15—1

FIG. 1 is a front perspective view of a child's convertible chair showing my new design in position for use as a car seat;

FIG. 2 is a perspective view of the chair of FIG. 1, wherein same has been converted to its position for use as a rocking chair;

FIG. 3 is a medial vertical sectional view taken along the line 3—3 of FIG. 2; and

FIG. 4 is a rear elevational view thereof.

I claim:

The ornamental design for a child's convertible chair, substantially as shown.
